[57] CLAIM

The ornamental design for a hockey garter, as shown and described.

DESCRIPTION

FIG. 1 is a top perspective view of a garter for holding up a sock worn by a hockey player, showing my new design;

FIG. 2 is a bottom perspective view of the hockey garter of FIG. 1;

FIG. 3 is a side elevational view thereof as viewed from either a left or right side edge of the hockey garter;

FIG. 4 is a side elevational view thereof as viewed from the top side edge of the hockey garter; and,

FIG. 5 is a side elevational view thereof as viewed from the bottom side edge of the hockey garter.

Fig.1.

Fig.2.

Fig.3.

Fig.4.
